UNITED STATES PATENT OFFICE.

CHARLES GRAFF, OF NEW YORK, N. Y., ASSIGNOR TO THE GRAFF, WASH-
BOURNE & DUNN, OF SAME PLACE.

DESIGN FOR METAL STOCK.

SPECIFICATION forming part of Design No. 32,035, dated December 26, 1899.

Application filed December 1, 1899. Serial No. 738,917. Term of patent 3½ years.

To all whom it may concern:

Be it known that I, CHARLES GRAFF, a citizen of the United States, residing at New York city, county of New York, and State of New York, have invented and produced a certain new and original Design for Metal Stock, fully described and represented in the following specification and the accompanying drawings, forming a part of the same.

- o In the drawings, Figure 1 is a plan or face view of a piece of metal stock embodying my design. Fig. 2 is an edge view of the same looking downward in Fig. 1. Fig. 3 is a cross-section on the line 3 of Fig. 1.
- 5 The essential feature of the design consists in the blossoms A, projecting from the body

of the metal or undercut, as shown in Figs. 2 and 3. With the blossoms A are combined the leaves B to form my design, and I have shown my design as provided with a border 20 finish consisting of the stem C.

What I claim is—

The design for metal stock, substantially as shown and described.

In testimony whereof I have hereunto set 25 my hand in the presence of two subscribing witnesses.

CHARLES GRAFF. [L. S.]

Witnesses:

CLEVELAND A. DUNN,
JOHN H. HANAN.
